UNITED STATES PATENT OFFICE.

ANDREW MESS, OF KILBOURN CITY, WISCONSIN.

MEDICAL INJECTOR.

SPECIFICATION forming part of Letters Patent No. 391,546, dated October 23, 1888.

Application filed August 16, 1888. Serial No. 282,849. (No model.)

To all whom it may concern:

Be it known that I, ANDREW MESS, a citizen of the United States, residing at Kilbourn City, Columbia county, Wisconsin, have invented 5 certain new and useful Improvements in Medical Injectors, of which the following is a specification.

The object of my invention is to provide an apparatus for injecting medical fumes or vapors into the bodies of human beings and beasts for curative purposes. I find that certain kinds of medicine injected into the body through some one of its openings—as, for instance, the rectum—is more effective than when taken internally in a solid or a liquid form.

My invention consists in a novel apparatus embodying a chamber for containing the medical substances, a nozzle at the front end of the chamber, a valve at the rear end, a plug in 10 rear of the valve having an extension passing through the valve and bellows secured to the plug.

My invention also consists in placing a perforated partition in front of the chamber for 15 containing the medical substances and in rear of a nozzle, on the outer end of which is a smooth round collar, the rear end of the chamber being provided with a hinged valve, behind which is located a screw-plug, to which 20 the bellows are secured.

In the accompanying drawings, Figure 1 is 25 a side elevation, and Fig. 2 a longitudinal central section, of the device.

The chamber A, for containing the medical 30 substances, is located within a cylindrical body, B, which is provided with a handle, B'. At its rear end the chamber A is enlarged to form a valve-chamber, a, and valve seat a' for the valve C, which is hinged at c, as shown, and is provided 35 with a handle, c'. The outer end of the valve-chamber a is screw-threaded internally, as shown, to receive the screw-threaded end of the plug D, which is provided with a flange-cap, d. The plug D is provided with an extension, d', 40 preferably conical or tapered, as shown, and having a conical or other shaped bore or opening, d². The extension d' passes through an opening, d³, in the valve C. When screwed home, the plug holds the valve shut.

45 An air-blast apparatus is placed at the rear

end of the cylinder, in this instance shown as consisting of a pair of bellows, E, of suitable construction, adapted for attachment to the cylinder. At its air-delivery end the bellows is provided with a nozzle which fits snugly into the opening d' of the screw-plug D. The bellows may be readily withdrawn and the screw-plug removed, thus allowing the valve C to be opened and access to be had to the chamber A. When thus opened, the medical ingredients may 55 be placed within the chamber A. The front end of the cylinder B is reduced and screw-threaded at b to receive the screw-threaded end of the front piece, F, which is preferably made to taper from its inner to its outer end. 60 Between the end of the cylinder B and the end of the front piece, F, is placed a perforated partition, f, through which the fumes or vapors from the chamber A may pass without carrying with them solid particles. The front piece, F, is hollow, the opening g preferably being tapered from its inner end outwardly, and the exterior of the front piece is preferably tapered in a similar way. The extreme outer end of the front piece is reduced and screw-threaded 65 at g' to receive the screw-threaded inner end of the nozzle G, which tapers to its outer end, where it is provided with a smooth round collar, h, adapted to enter the animal's body without injury. The nozzle may be varied in size 70 and character to suit different persons and beasts. As will be seen, the nozzle may be readily unscrewed and replaced.

As before stated, the ignited medical substances are placed in the chamber A, when the 75 bellows and screw-plug are removed and the valve C open. When the valve is closed and the screw-plug and bellows in position, air may be forced through the chamber A, so as to promote combustion and carry the fumes or vapors 80 through the perforated partitions f out through the nozzle G. The force of the current of air may be regulated by properly operating the bellows.

90 Any suitable medical substances may be employed in my apparatus, and may be changed to suit the disease to be treated. Incense and flavauna are both medicines to restore pressure in the breast, lungs, or stomach. When 95 the fumes or vapors from the substance are in- 100

jected into the body, they will break through all obstructions and put the affected parts in their normal condition.

I claim as my invention—

5 1. The combination, substantially as hereinbefore set forth, of the chamber for containing the medical substances, a nozzle at the front end of the chamber, a valve at the rear end, the plug in rear of the valve having an exten-
10 sion passing through the valve, and the bellows secured to the plug.

2. The combination, substantially as hereinbefore set forth, of the cylindrical body B, having a chamber, A, for containing the medical substances, the front piece, F, the perforated

partition f between the front piece and the cylindrical body and at the front end of the chamber A, the removable nozzle on the end of the front piece having a smooth round collar, h, on its outer end, the hinged valve at the rear of the chamber A, the screw-plug D behind the valve, and the bellows secured to the plug. 20

In testimony whereof I have hereunto subscribed my name.

ANDREW MESS.
